ABSTRACT

Apparatus for feeding the objects to be stamped in front of a device for printing the stamps on the objects. The printing device has a printing surface inking up sub-assembly which is accessible and removable and a printing sub-assembly including a printing surface carrier and enclosed in a completely closed case. An electronic sub-assembly, also completely enclosed, has a counting circuit connected to a device detecting the passage of the objects in front of the printing device, and a safety circuit.

15 Claims, 3 Drawing Figures

FIG. 1

FIG. 3

MACHINE FOR PRINTING STAMPS, IN PARTICULAR ON BOTTLE CAPS

The present invention relates to a machine for printing stamps on objects and in particular inspection or tax stamps on closing members such as bottle caps.

In such a machine, it must be impossible to print such stamps without the stamps being counted by a counting device included in the machine. It is known, for example from French Pat. No. 1,349,899, to construct machines of this type in which one or more printing stamps are moved inside a case so as to bring them in contact with the object to be printed. These machines have the drawback of being discontinuous in operation. Moreover, as they are almost entirely mechanical they are particularly complex and expensive and do not allow a high printing rate.

An object of the present invention is to overcome these drawbacks.

The invention provides a machine for printing stamps on objects of the type comprising a device for feeding the objects and a device for printing the objects, wherein the printing device comprises a sub-assembly for inking up the printing surface and accessible and capable of being disassembled, a printing sub-assembly comprising a printing surface carrier and disposed in a chamber of a perfectly closed case, and an electronic sub-assembly also perfectly enclosed and comprising a counting circuit connected to a device for detecting the passage of the objects and a safety circuit.

This machine is therefore simple in construction and cheap and precludes any fraudulent utilization.

Further features and advantages of the invention will be apparent from the ensuing description with reference to the accompanying drawings.

In the drawings:

FIG. 1 is a diagrammatic elevational view of a machine according to the invention for printing a stamp or mark on metal caps for bottles;

FIG. 2 is a partial sectional view to an enlarged scale taken on line 2-2 of FIG. 1, and

FIG. 3 is a diagram of the circuitry of the electronic sub-assembly of the machine.

The machine shown in the drawings comprises a fixed table 1 for supporting bottles B and integral with a fixed vertical frame 2, a device A for feeding the bottles and a printing device I.

The bottle feeding device A comprises a disc 3 having notches 4 or a star-shaped member which is disposed above the table 1 and parallel to the latter and is driven in rotation by a motor 5 through the output shaft 6 or this motor, bevel gears 7 and a shaft 8 to which the disc 3 is fixed.

The printing device I is integral with the frame 2 and disposed above a region in which the disc 3 brings the bottles B to be printed. It is adjustable in height by means of a device (not shown) so as to adapt it to the variable height of the bottles to be printed. The printing device is of the offset type and comprises a sub-assembly E for inking up the printing surface, or plate, a sub-assembly D for printing the printing surface on the caps C and an electronic sub-assembly F for detecting the caps and counting the printings.

The inking up and printing sub-assemblies E and D are disposed in a common case 9 having two adjacent chambers which are separated by a partition wall, namely a chamber 9^a open in its upper part and enclos-

ing the inking up sub-assembly E and a chamber 9^b which is substantially closed and rendered inaccessible or tamper-proof by a sealed wall 9^c which encloses the printing sub-assembly D.

5 The inking up sub-assembly E is detachably mounted in the chamber 9^a of the case and comprises two parallel support plates 10 which carry an ink supply tank 11 open on a lateral side, a roller 12 for taking up ink tangent to the edge of the opening of the tank 11, ink 10 transfer roller which is displaced by a device (not shown) of the type conventionally employed in offset printing machines so as to come in contact alternately with the roller 12 and with a roller 14 which is tangent to an inkspreading roller 15 and a last roller 16 tangent to the roller 14 and provided for inking up the printing surface.

The roller 14 is rotated by the motor 5 through a belt 17 which extends around the shaft 14^a of the roller 14. The rollers 13, 15 and 16 are freely rotative on their 20 shafts 13^a, 15^a and 16^a and are driven in rotation at least by the drive roller 14 to which they are tangent. The roller 12 is periodically driven in rotation by the roller 14 through a device (not shown) also of the type conventionally employed in offset printing machines.

25 The detachable sub-assembly E is supported by the shaft 14^a of the roller 14 which extends through the walls of the case 9 and it is maintained in position in the chamber 9^a by lugs 18 which are integral with the upper part of the support plate 10 and bear against heads of screws 19 screwed in bosses 20 on the case 9 and on the other hand by a cross member 21 which connects the lower parts of the two support plates 10 and bears against a screw 22 screwed in the case 9.

30 The printing sub-assembly D is disposed in the chamber 9^b of the case and comprises a printing surface or plate carrying roller 23 which carries an image of the stamp to be printed and which is tangent to the inking up roller 16 of the sub-assembly E through an opening 9^d which puts the two chambers 9^a and 9^b in communication with each other. This roller 23 is also tangent to a printing or transfer roller 24 which slightly projects beyond the lower face of the case through an opening 9^e of the chamber 9^b. Located on each side of the printing roller 24 and perpendicular to its axis are two devices for erasing this roller, each of which comprises fixed to one end of a rod 25 an erasing finger portion 26 sliding in a guide 27 integral with the case 9 and an electromagnet 28 for maintaining the finger member 26 separated from the roller 24 in opposition to the action of a spring 29. The printing surface carrying roller 23 and printing roller 24 are driven by their shafts 23^a and 24^a around which the belt 17 extends.

35 The electronic sub-assembly F is, except for means for measuring the speed of rotation of the motor and two detectors detecting the presence of the caps C, placed in a case 30 adjacent the case 9 and closed by a sealed cover which therefore prevents access to the inside of the case 30. The means for measuring the speed of rotation of the motor is a tachometric dynamo 31 which is screwed on the shaft of the motor 5. An inductive detector 32 of the presence of a metal cap C of a bottle is placed under the case 9 in the vicinity of the opening 9^b and printing roller 24. The zone of detection of this detector 32 is located upstream of the printing roller 24 with respect to the direction S of feed of the caps C to be printed so as to detect the caps slightly before their printing. A second inductive detector 33 is placed next to the detector 32 in alignment

with the axis of the printing roller 24 so as to detect the caps at the very moment of their printing.

Apart from the detectors 32 and 33 and the dynamo 31, the sub-assembly comprises a pulse generator 34 of the hybrid monostable type (flipflop + a uni-junction timing circuit) having an input connected to the first detector 32 but having moreover a second input connected to the tachometric dynamo 31, this generator producing at a first output 34^a, when actuated by the detector 32, a signal of duration which is governed by — or more precisely inversely proportional to — the speed of the dynamo (the voltage of the latter being applied to the terminals of the capacitor of the RC circuit of the generator). In the absence of a signal at this output 34^a there is a signal at its second output 34^b. From any one of its inputs to output 34^a and output 34^b, the generator 34 defines signal generator means and signal generating means respectively. This generator 34 is connected, on one hand through its output 34^a, to an electronic AND gate or element 35, and, on the other hand through its output 34^b, to an input of another AND gate or element 36. The other input of the gate 35 is connected to the second detector 33 and its output is connected to an electromechanical pulse counter 37. Connected in parallel with this counter 37 is an electronic device 38 adapted to check whether the counter has moved forward one unit in a normal interval of time for its advance. In the case of imperfect operation of the counter 37, this device sets off an alarm 39 and stops the motor 5.

The first detector 32 is also connected to a bistable circuit or flipflop 40 which, under the effect of a pulse from the detector 32, delivers a signal at one, namely 40^a, of its outputs. There is then no signal at its second output 40^b. From any one of its inputs to output 40^a and output 40^b, the flipflop 40 defines a signal generator circuit and a signal generating circuit respectively. A reset signal of this flipflop which inverts the position of the signal at the output of this flipflop is furnished through an INCLUSIVE OR gate or element 41, either by a pulse from the electromechanical counter 37 or by a safety key contact 42. The output 40^a of the flipflop 40 is connected to a second input of the AND gate 36 and its output 40^b to an input or an electronic AND gated or element 43 whose second input is connected to the second detector 33.

The second detector 33 is also connected between the second input of the AND gate 43, to a third input of the AND gate 36. The outputs of the gates 36 and 43 are connected through electronic INCLUSIVE OR gate or element 44 to an alarm device 45 which stops the machine. The alarm and machine stopping devices 39, 45 can only be neutralized by actuation of the key safety contact 42 which also once more starts up the machine.

The machine just described operates in the following manner:

In normal operation, the sub-assembly E for inking up the printing surface is placed in the chamber 9^a of the case 9, the positioning screw 22 being screwed in such manner that the inking up roller 16 comes in contact with the printing surface carrying roller 23. The bottles B with their metal caps C are fed under the printing device I by the notches 4 of disc 3 which is driven by the motor 5. The motor 5 also drives the rollers 14, 22 and 24. Thus, as it is rotated by the roller 14, the roller 11 takes ink from the tank 12 and transmits this ink to the roller 14 through the transfer roller

13, the spreading roller 15 spreading the ink in a continuous film on the roller 14. The latter transfers its ink to the inking up roller 16 which then inks up the printing surface carried by the roller 23. The latter then deposits or prints an image of the printing surface on the printing roller 24 which prints this image when it passes over the cap C through the opening 9^a of the case 9.

When the metal cap C passes in front of the first detector 32, the latter sends a pulse to the generator 34 which then delivers at its output 34^a a signal of a length inversely proportional to the speed measured by the tachometric dynamo 31. This length of the signal is therefore also inversely proportional to the rate of feed of the bottles B which are fed by the disc 3 driven by the motor 5. The length of the signal is such that at the normal rate of feed of the bottles, the metal cap C passes in front of the second detector 33 before the end of the signal. In this case, the detector 33 delivers a pulse upon the passage of the cap C, that is to say at the moment of the printing of this cap by the roller 24, and this pulse is combined in the AND gate 35 with that of the signal delivered at the output 34^a of the generator 34. This gate 35 then delivers a pulse which actuates the electromechanical counter 37 and causes the latter to count one unit more. Thus, one count corresponds to each printing of an image or stamping.

When the machine is started up, the flipflop 40 is in such state that there is no signal at its output 40^a and a signal at its output 40^b. Upon the passage of a cap in front of the detector 32, the latter sends a signal to the flipflop 40 which produces a signal at its output 40^a and suppresses the signal at its output 40^b. Upon the passage of the cap in front of the detector 33, the latter sends a signal to the AND gate 36 which already receives a signal from the output 40^a of the flipflop but receives nothing from the output 34^b of the monostable element so that this gate 36 does not set off the alarm 45.

When the electromechanical counter 37 has advanced one unit after the passage of the cap in front of the detector 33, this counter sends a pulse through the INCLUSIVE OR gate 41 to the flipflop 40 which resumes its initial state so as to permit the following counting without setting off the alarm.

Starting up the machine requires, before printing the caps C, that the rollers rotate several times in order to achieve the correct inking up of the printing surface on the roller 23 and therefore of the printing roller 24. Consequently, it is essential to be able to operate the machine without bottles and without counting whereas, on the other hand, it is essential that the actual marking of a metal cap C of a bottle results in a count. The presence of the detectors 32 and 33 satisfies these requirements, since there is no counting if the two detectors do not produce pulses, that is to say, when there is no bottle. On the other hand, as soon as bottle caps are detected under normal conditions of operation, the electromechanical counter 37 is operative.

The electronic sub-assembly F also has for function to prevent any risk of fraud or error and a printing of the caps without counting.

Indeed, if for any reason the electromechanical counter 37 no longer operates in normal operation of the machine and if the rate of advance of the counting wheels of the counter decreases, for example owing to a soiling of the wheels, the device 38 for checking that there is a normal advance of the counter sets off an

alarm and stops the machine.

Moreover, if it were attempted to introduce bottles in a direction opposed to the normal direction S, the metal cap C would pass under the second detector 33 before passing under the first detector 32 so that there would be no coincidence between the pulse of the detector 33 and the signal which is normally delivered by the output 34^a of the generator 34 as a consequence of the actuation of the latter by the detector 32. Consequently, no counting could occur, since the AND gate 35 would not be actuated. Moreover, the pulse of the second detector 33 would coincide with a signal which is given by the output 40^b of the flipflop 40 bearing in mind that no signal is given by the first detector 32. These signals would give a signal at the output of the AND gate 43 and this signal would then set off an alarm and cause the complete stoppage of the machine by the action of the OR gate 44. Consequently, the machine could only be started up again by re-inserting the safety contact key 42 which flips the flipflop 40 and thus suppresses the signal delivered at the output 40^b.

Also, if the cap C to be printed passes in front of the first detector 32 before passing in front of the second detector but too slowly with respect to the speed measured by the tachometric dynamo 31, the pulse of the detector 33 would not occur during the prolonged signal delivered by the generator 34 at its output 34^c as a consequence of the actuation of the latter by the detector 32. In this case, the pulse delivered by the detector 33 would occur whereas the generator 34 would be at rest, with a signal delivered at the output 34^b. At this moment, a signal would also be delivered at the output 40^a of the flipflop 40 owing to the actuation of the latter by the detector 32. These three united signals would then actuate the AND gate 36 and would set off the alarm and cause stoppage of the machine by the action of the OR gate 44. The starting up of the machine and the suppression of the alarm could then only be achieved by actuating the safety key contact 42.

Finally, in the event of the current being cut off, it is impossible to cause a printing by manual operation, for example by turning by hand the shaft 14^a of the roller 14 since in this case the electromagnets 28, which are located in the case and are supplied with current by a normal current supply, are no longer carrying current and the erasing finger members 26 are biased by the springs 29 in the guides 27 and bear against the printing roller 24 from which they remove any image of the printing surface.

Owing to the offset type printing, the stamping of the caps is achieved in a continuous manner. The printing device is simple, since it only comprises rotating rollers without parts which move in translation or in a reciprocating manner.

When the machine is stopped, the sub-assembly E for inking up the printing surface to be printed, may be easily cleaned since it is sufficient to unscrew the screw 22 and raise the support plates 10 which carry therewith the rollers 12, 13, 14, 15 and 16 and the ink supply tank 11.

Another advantage of the invention resides in the simplification of the mechanical parts of this machine, due to the utilization of an electronic system for counting, detecting the caps, actuating the machine and detecting fraudulent use.

An improvement of the invention would consist in employing an ink having a resin base which would be

polymerized immediately under the effect of a suitable radiation. For drying the ink it would then be sufficient to provide following on the printing device a source of radiation directed onto the upper part of the caps as they issue from below this device.

Having now described my invention what I claim as new and desire to secure by letters patent is:

1. A machine for printing stamps on objects, comprising a device for printing the objects and a device for feeding the objects to the printing device, the printing device comprising a case defining a chamber which is closed except for a first opening and a second opening, a printing sub-assembly disposed in the chamber and comprising roller means defining a first surface for receiving ink and roller means defining a second surface which is positioned for applying an ink stamp on each object through said first opening, a second sub-assembly which has roller means for inking up the first surface and is accessible and removable from the printing device, said first surface and said roller means of the second sub-assembly being in interengagement through said second opening, said first opening and second opening being just sufficient to allow application of the ink stamp on the object and inking of the first surface while rendering access to the inside of said chamber difficult, an electronic sub-assembly, means enclosing the electronic sub-assembly to render the electronic sub-assembly normally inaccessible, a device for detecting the passage of each object adjacent the printing sub-assembly to a position for the printing of the stamp on the object by the printing sub-assembly, the detecting device including a circuit producing an electrical signal upon detection of each object, the electronic sub-assembly comprising circuitry including the circuit of the detecting device and a counting circuit connected to the circuit of the detecting device to be responsive to the production of said signal, and a safety circuit associated with said circuitry to check correct operation of said circuitry upon passage of each object to said position for printing and operative to stop operation of the machine in the event of incorrect operation of said circuitry.
2. A machine as claimed in claim 1, wherein the counting circuit comprises a counter having terminals, the safety circuit comprises a circuit which is for checking that the counting is effected and is connected to the terminals of the counter and has an output connected to means for giving an alarm and stopping operation of the machine.
3. A machine for printing stamps on objects, comprising a device for printing the objects and a device for feeding the objects to the printing device, the printing device comprising a case defining a chamber which is closed except for a first opening and a second opening, a printing sub-assembly disposed in the chamber and comprising a first roller, means defining a printing surface carried by the first roller and a transfer roller which is engaged with the printing surface and positioned for applying an ink stamp on each object through said first opening, a sub-assembly which is for inking up the printing surface and is accessible and removable from the printing device, the inking up sub-assembly comprising, in the manner of an offset printing machine, inking up rollers for inking up the printing surface, the inking up rollers including a second roller in engagement with said first roller through said second opening, said first opening and second opening being just sufficient to allow application of the ink stamp on

the object and inking of the first roller while rendering access to the inside of said chamber difficult, an electronic sub-assembly, means enclosing the electronic sub-assembly to render the electronic sub-assembly ordinarily inaccessible, a device for detecting the passage of each object adjacent the printing sub-assembly to a position for the printing of the stamp on the object by the printing sub-assembly, the detecting device including a circuit producing an electrical signal upon detection of each object, the electronic sub-assembly comprising circuitry including the circuit of the detecting device and a counting circuit connected to the circuit of the detecting device to be responsive to the production of said signal, and a safety circuit associated with said circuitry to check correct operation of said circuitry upon passage of each object to said position for printing and operative to stop operation of the machine in the event of incorrect operations of said circuitry.

4. A machine as claimed in claim 3, wherein the printing sub-assembly comprises on a side of the transfer roller at least one erasing element, an electromagnet, and spring means biasing the erasing element toward the transfer roller, the electromagnet being for connection to a power supply which also supplies power to the machine to be operative in opposition to the action of the spring means to move the erasing element away from the transfer roller when power is supplied to the machine.

5. A machine as claimed in claim 3, wherein the case defines a second chamber to which free access can be had and support means are removably mounted in the second chamber and carry the inking up rollers.

6. A machine for printing stamps on objects, comprising a device for printing the objects and a device for feeding the objects to the printing device, the printing device comprising a case defining a chamber which is closed except for a first opening and a second opening, a printing sub-assembly disposed in the chamber and comprising roller means defining a first surface for receiving ink and roller means defining a second surface which is positioned for applying an ink stamp on each object through said first opening, a second sub-assembly which has roller means for inking up the first surface and is accessible and removable from the printing device, said first surface and said roller means of the second sub-assembly being in interengagement through said second opening, said first opening and second opening being just sufficient to allow application of the ink stamp on the object and inking of the first surface while rendering access to the inside of said chamber difficult, an electronic sub-assembly, means enclosing the electronic sub-assembly to render the electronic sub-assembly normally inaccessible, a device for detecting the passage of each object adjacent the printing sub-assembly to a position for the printing of the stamp on the object by the printing sub-assembly, the detecting device including a circuit producing an electrical signal upon detection of each object, the electronic sub-assembly comprising circuitry including the circuit of the detecting device and a counting circuit connected to the circuit of the detecting device to be responsive to the production of said signal, and a safety circuit associated with said circuitry to check correct operation of said circuitry upon passage of each object to said position for printing and operative to stop operation of the machine in the event of incorrect operation of said circuitry, the feeding device impart-

5 ing a path of travel to the objects and the device for detecting the passage of the objects comprising two detectors disposed one following the other in said path of travel of the objects, a first detector being upstream of a region in which the second surface prints the stamp on each object and the second detector being located in alignment with said region, the first detector and the second detector being each capable of producing a pulse upon detection of an object, and the counting circuit comprising a signal generator means for generating signals of duration a little longer than the time the feed device takes to move an object between the two detectors, the signal generator means having an input connected to the first detector and an output, a counter, and an AND circuit having a first input connected to said output of the signal generator means, a second input connected to the second detector and an output connected to the counter, the safety circuit comprising a signal generating circuit having an input connected to the first detector and an output, the signal generating circuit being capable of generating signals at its output when there is no pulse at the input of the signal generating circuit, a second AND circuit having a first input connected to the output of the signal generator means, a second input connected to the second detector and an output, and means for giving an alarm and stopping operation of the machine and connected to the output of the second AND circuit, a signal generator circuit having an input and an output for generating signals at its output when a pulse arrives at its input which input is connected to the first detector, and signal generating means having an input connected to the first detector and an output and capable of generating signals at its output after a lapse of time exceeding the time the feeding device takes to feed an object between the two detectors following on the arrival of a pulse at the input of the fourth circuit, means for giving an alarm and stopping the machine, and a third AND circuit having three inputs respectively connected to the outputs of the signal generator circuit and signal generating means and to the second detector and an output connected to the means for giving an alarm and stopping operation of the machine.

7. A machine for printing stamps on objects, comprising a device for printing the objects and a device for feeding the objects to the printing device, the printing device comprising a case defining a chamber which is closed except for a first opening and a second opening, a printing sub-assembly disposed in the chamber and comprising roller means defining a first surface for receiving ink and roller means defining a second surface which is positioned for applying an ink stamp on each object through said first opening, a second sub-assembly which has roller means for inking up the first surface and is accessible and removable from the printing device, and first surface and said roller means of the second sub-assembly being in interengagement through said second opening, said first opening and second opening being just sufficient to allow application of the ink stamp on the object and inking of the first surface while rendering access to the inside of said chamber difficult, an electronic sub-assembly, means enclosing the electronic sub-assembly to render the electronic sub-assembly normally inaccessible, a device for detecting the passage of each object adjacent the printing sub-assembly to a position for the printing of the stamp on the object by the printing sub-assembly, the detecting device including a circuit producing an electrical signal upon detection of each object,

signal upon detection of each object, the electronic sub-assembly comprising circuitry including the circuit of the detecting device and a counting circuit connected to the circuit of the detecting device to be responsive to the production of said signal, and a safety circuit associated with said circuitry to check correct operation of said circuitry upon passage of each object to said position for printing and operative to stop operation of the machine in the event of incorrect operation of said circuitry, the feeding device imparting a path of travel to the objects and the device for detecting the passage of the objects comprising two detectors disposed one following the other in said path of travel of the objects, a first detector being upstream of a region in which the second surface prints the stamp on each object and the second detector being located in alignment with said region, and the counting circuit comprising signal generator means for generating signals of duration a little longer than the time the feed device takes to move an object between the two detectors, the signal generator means having an input connected to the first detector and an output, a counter, and an AND circuit having a first input connected to said output of the signal generator means, a second input connected to the second detector and an output connected to the counter.

8. A machine as claimed in claim 7, wherein the signal generator means have a second input, the machine comprising a motor for driving the device for feeding the objects to the printing device and a tachometric dynamo drivingly connected to the motor and electrically connected to the second input of the signal generator means to control the duration of the signals.

9. A machine for printing stamps on objects, comprising a device for printing the objects and a device for feeding the objects to the printing device, the printing device comprising a case defining a chamber which is closed except for a first opening and a second opening, a printing sub-assembly disposed in the chamber and comprising roller means defining a first surface for receiving ink and roller means defining a second surface which is positioned for applying an ink stamp on each object through said first opening, a second sub-assembly which has roller means for inking up the first surface and is accessible and removable from the printing device, said first surface and said roller means of the second sub-assembly being in interengagement through said second opening, said first opening and second opening being just sufficient to allow application of the ink stamp on the object and inking of the first surface while rendering access to the inside of said chamber difficult, an electronic sub-assembly, means enclosing the electronic sub-assembly to render the electronic sub-assembly normally inaccessible, a device for detecting the passage of each object adjacent the printing sub-assembly to a position for the printing of the stamp on the object by the printing sub-assembly, the detecting device including a circuit producing an electrical signal upon detection of each object, the electronic sub-assembly comprising circuitry including the circuit of the detecting device and a counting circuit connected to the circuit of the detecting device to be responsive to the production of said signal, and a safety circuit associated with said circuitry to check correct operation of said circuitry upon passage of each object to said position for printing and operative to stop operation of the machine in the event of incorrect operation of said circuitry, the feeding device impart-

ing a path of travel to the objects and the device for detecting the passage of the objects comprising two detectors disposed one following the other in said path of travel of the objects, a first detector being upstream of a region in which the second surface prints the stamp on each object and capable of producing a pulse upon detection of an object and the second detector being located in alignment with said region and capable of producing a pulse upon detection of an object, the safety circuit comprising a signal generating circuit having an input connected to the first detector and an output, the signal generating circuit being capable of generating signals at its output when there is no pulse at the input of the signal generating circuit, and AND circuit having a first input connected to the output of the signal generating circuit, a second input connected to the second detector and an output, and means for giving an alarm and stopping operation of the machine and connected to the output of the AND circuit.

20 10. A machine for printing stamps on objects, comprising a device for printing the objects and a device for feeding the objects to the printing device, the printing device comprising a case defining a chamber which is closed except for a first opening and a second opening,

25 a printing sub-assembly disposed in the chamber and comprising roller means defining a first surface for receiving ink and roller means defining a second surface which is positioned for applying an ink stamp on each object through said first opening, a second sub-assembly which has roller means for inking up the first surface and is accessible and removable from the printing device, said first surface and said roller means of the second sub-assembly being in interengagement through said second opening, said first opening and second opening being just sufficient to allow application of the ink stamp on the object and inking of the first surface while rendering access to the inside of said chamber difficult, an electronic sub-assembly, means enclosing the electronic sub-assembly to render the electronic sub-assembly normally inaccessible, a device for detecting the passage of each object adjacent the printing sub-assembly to a position for the printing of the stamp on the object by the printing sub-assembly, the detecting device including a circuit producing an electrical signal upon detection of each object, the electronic sub-assembly comprising circuitry including the circuit of the detecting device and a counting circuit connected to the circuit of the detecting device to be responsive to the production of said signal, and a safety circuit associated with said circuitry to check correct operation of said circuitry upon passage of each object to said position for printing and operative to stop operation of the machine in the event of incorrect operation of said circuitry, the feeding device imparting a path of travel to the objects and the device for detecting the passage of the objects comprising two detectors disposed one following the other in said path of travel of the objects, a first detector being upstream of a region in which the second surface prints the stamp on each object and capable of producing a pulse upon detection of an object and the second detector being located in alignment with said region and capable of producing a pulse upon detection of an object, the safety circuit comprising a signal generating circuit having an input and an output for generating signals at its output when a pulse arrives at its input which input is connected to the first detector, and signal generating means having an input connected to the first detector

30 35 40 45 50 55 60 65

and an output and capable of generating signals at its output after a lapse of time exceeding the time the feeding device takes to feed an object between the two detectors following on the arrival of a pulse at the input of the signal generating means, means for giving an alarm and stopping the machine, and an AND circuit having three inputs respectively connected to the outputs of the signal generator circuit and signal generating means and to the second detector and an output connected to the means for giving an alarm and stopping operation of the machine.

11. A machine as claimed in claim 10, wherein the signal generator circuit has a second input and the safety circuit further comprises re-starting means connected to the second input of the signal generator circuit, the signal generator circuit being adapted and arranged to give no pulse at its output when a pulse arrives at said second input of the signal generator circuit.

12. A machine as claimed in claim 11, wherein the safety circuit comprises a signal generating circuit having an input connected to the first detector and an output, the signal generating circuit being capable of generating signals at its output when there is no pulse at the input of the signal generating circuit connected to the output of the second circuit, a second AND circuit having a first input connected to the output of the signal generating circuit, a second input connected to the second detector and an output, and means for giving an alarm and stopping the machine and connected to the output of the second AND circuit, the counting circuit having an output, the signal generating circuit and the signal generator circuit being constituted by a single flipflop which has a first input connected to the first detector and a second input connected to means for re-starting the machine and to the output of the counting circuit through an INSLUSIVE OR circuit, the flipflop having two outputs respectively constituted by

40

said output of the signal generator circuit and said output of the signal generating circuit.

13. A machine as claimed in claim 10, wherein the signal generator circuit has a second input and the counting circuit has an output which is connected to the second input of the signal generator circuit which signal generator circuit is adapted and arranged to deliver no pulse at its output when a pulse arrives at said second input of the signal generator circuit.

14. A machine as claimed in claim 10, wherein the signal generator circuit has a second input and the safety circuit further comprises re-starting means connected to the second input of the signal generator circuit, the signal generator circuit being adapted and arranged to give no pulse at its output when a pulse arrives at said second input of the signal generator circuit, the machine further comprising an INCLUSIVE OR circuit having two inputs and an output, the re-starting means and the output of the counting circuit being connected to the two inputs of the INCLUSIVE OR circuit whose output is connected to the second input of the signal generator circuit.

15. A machine as claimed in claim 10, wherein the counting circuit comprises signal generator means for generating signals of duration a little longer than the time the feed device takes to move an object between the two detectors, the signal generator means having an input connected to the first detector and an output, a counter, and a second AND circuit having a first input connected to said output of the signal generator means, a second input connected to the second detector and an output connected to the counter, the signal generator means and the signal generating means being constituted by a single circuit of the monostable type having an input connected to the first detector and two outputs which are respectively constituted by said output of the signal generator means and said output of the signal generating means.
